REINHOLD KRUMMING, OF MILWAUKEE, WISCONSIN.

ATTACHMENT MEANS FOR BINDER-POSTS.

No. 911,050.

Specification of Letters Patent.

Patented Feb. 2, 1909.

Application filed May 23, 1908. Serial No. 434,494.

To all whom it may concern:

Be it known that I, REINHOLD KRUMMING, of Milwaukee, Wisconsin, have invented an Attachment Means for Binder-Posts, 5 of which the following is a specification.

In my copending United States patent application No. 308,168, filed March 26, 1906, I have shown an improved means for attaching tubular posts to binder-backs, the 10 same consisting of a pair of plates or disk-shaped elements screwed upon the end of the post-section on opposite sides of a thin bendable sheet-metal base or body which they clamp between them,—a great advance 15 over the old method of screwing the post directly into a rigid back which was current prior to my advent in the field, since the latter construction is subject to serious disadvantages, among others those of easily 20 breaking off at the base and of becoming loose and coming out accidentally, which is due to the necessary fineness of the threads, the shortness of the threaded portion, and the constant side-strains upon the post.

25 In my copending application No. 409,273, filed Jan. 4, 1908, I have disclosed and claimed a still further and great improvement upon the screwed clamping-plates or nuts of my first said application, since there- 30 in I have shown a means of dispensing with the threads entirely and thus securing not only a much stronger and more rigid but also a cheaper means of attachment.

35 My present application comprises a still further improvement of the attachment-means of my two former applications, since I have succeeded in making the post-section with the attachment-means thereon removable from the binder-back; and by my im- 40 proved construction I in addition make the device fully as cheap if not cheaper than before, and also fully as strong.

Briefly, in my present invention I unite 45 the two clamping-plates of my aforesigned application into a single element or member which is adapted to slide in edgewise through a buttonhole-slot in the edge of the bendable sheet-metal strip which forms the body or base of the binder-back.

50 The nature of my invention will be best and more precisely understood by a consider- 55 ation of the following description of the most improved form thereof, taken in connection with the accompanying drawings illustrative of the same.

In these drawings, Figure 1 is a side eleva-

tion of a post-section and binder-back showing the attachment-means in mounted position; Fig. 2 is a longitudinal central section through the same in a parallel plane, the filling-pads and covering being omitted in this view; Fig. 3 is a side elevation in a plane at right angles to Fig. 1 of the post and attachment-means separately; Fig. 4 is a plan view of the parts shown in Fig. 1 with the canvas 60 or leather covering-sheet removed; Fig. 5 is a plan-section of the same taken in the plane of the upper surface of the sheet-metal base; Fig. 6 is a similar cross-section with the post and attachment-piece turned at right angles, 65 in position of removal or insertion; Fig. 7 is a plan of a portion of the sheet-metal base showing the button-hole slot; Fig. 8 is a plan-section the same as Fig. 5 of the post and attachment-piece separately; Fig. 9 is a 70 perspective view of the attachment-piece; Fig. 10 is a perspective view of the upper end of the attached end of the post; Fig. 11 is a plan of a post-end constructed according to the principles of my invention without 75 the attachment-piece; Fig. 12 is a plan-section of the same in the plane of the annular groove thereof; Fig. 13 is a side elevation of the same; and Fig. 14 is a longitudinal section of the same; the post being turned at 80 right angles in this figure and Fig. 12.

In these drawings, every reference letter and numeral refers always to the same part.

Referring first to Figs. 1 to 10 inclusive, the binder-back is designated *a* and the post- 90 section *b*. Said binder-back is, in the most improved form of my invention, made of bendable sheet metal; although it is not confined thereto, as it could be constructed on the same principle with rigid or cast metal or 95 other material.

The improved post *b* is attached to the base *a* by means of the intermediary element *c*, herein designated the attachment-piece. Said attachment-piece will ordinarily be 100 punched into the outline shown from a strip of sheet metal, and will subsequently have two saw-cuts *c'* on opposite sides thereof and in the plane of the flat surfaces, said saw-cuts extending slightly within the margin of the 105 circular central body *c²*, so as to form flats *c³* on opposite sides; whereby said saw-cuts leave a pair of projecting-flanges *c⁴* on opposite sides of said saw-cuts. The saw-cuts are of the exact thickness of the base *a*, or as 110 closely as possible so, whereby the latter is received and fits closely between them as

shown in Fig. 2. The central body c^2 is made of the same diameter as the internal bore of the post b ; and the end of the latter is cut away on opposite sides to form flats 5 b' , leaving abutment shoulders b^2 at the bottom, and forming thus a pair of upstanding tabs b^3 which fit neatly between the two projecting ends of the flanges c^4 of the attachment-piece, when the central body c^2 of the 10 latter is inserted between them into the bore of the post; and when the attachment-piece is in place on the post, the projecting ends of the tabs b^3 are flattened or clinched down over the upper surface thereof as clearly 15 shown in Figs. 1 to 4 inclusive.

The base a has a buttonhole-slot as shown in Fig. 7, the same comprising a circular hole a' of the same diameter of the post and provided with a side-outlet a^2 the width of which 20 is the same as that across the flats b' and c^3 of the post and attachment-piece; whereby the latter, when mounted together as in Fig. 3, will slide through the opening, in the position of Fig. 6, and when it reaches the circular 25 portion can be rotated therein into position at right angles to its entering position, as shown in Fig. 5, in which latter position it cannot be removed.

Where the post is to be frequently removed this will complete the operation of inserting it in place, and no further means for holding it there is necessary, since there is no force tending to rotate it and sufficient friction to keep it from rotating under ordinary 30 circumstances. Side-strains upon the post will simply cause a bending of the back a adjacent to the base of the post, and I have found by experience that this does not loosen the post but actually tightens the same, because 35 the bending of the edges of the hole a' disturbs the regularity of the surface of the base and tends to make it bind tighter between the flanges c^4 .

If it be desired to nonremovably secure the 40 post to the base, it is simply necessary to hammer the flanges c^4 together so as to produce a riveting effect which effectively prevents any rotative movement. However, as such riveting is very inconvenient when it is 45 desired to get the post loose again, I prefer to use some such means as shown in Figs. 1 and 4 to prevent the post from rotating until it is desired to remove it. In these figures the binder-back is shown complete, there being 50 pasteboard pads or cushions d and e secured to opposite sides of the base a , the pad d being of the same thickness as the flanges c^4 and the pad e being somewhat thicker so that its outer surface is flush with the tops of 55 the tabs b^3 ; and each pad has a recess, d' , e' , cut therein to receive these elements. The whole is covered with a suitable fabric such as canvas or leather f . I have heretofore, in my aforesaid application No. 308,168, 60 shown similar pads or cushions in connection

with the clamping-nuts or plates on the end of the post; and I utilize one of said cushions herein for holding the post against rotating by forming a projecting tab e^2 on the edge of the recess e' , which tab is of the proper form 70 and position to fit between the flanges c^4 as shown in Fig. 4. With this construction, the tab e^2 is protected and held in place by the covering sheet f , and when it is desired to remove the post, the sheet f is pulled up 75 so as to uncover the tab e^2 , which latter is then pried out of the recess between the flanges c^4 , and the post can be rotated and removed, and replaced if desired by another post which is inserted, rotated, and held by the tab e^2 as before, the covering-sheet f being gummed down over it or otherwise secured.

While the form described with the attachment-piece c is much the preferable one, it is 85 possible to attach the post directly to the base without the intermediary of the attachment-piece, which construction is shown in Figs. 11 to 14. As the metal of the post g is ordinarily very thin, it is necessary or desirable to insert a plug h in the end thereof. The attached end of the post is annularly grooved as shown at g' , the holes a' in the base being in this case made of the diameter of the bottom of said groove, and there are 90 cut on opposite sides of said groove flats g^2 , the width across said flats being the same as that across the side-outlet a^2 .

It is very desirable to have the posts easily removable from the back for a number of 100 reasons. For example, the user of the binder often desires to change a short for a long set of posts, or vice versa, in accordance with the number of sheets in the binder; or he may wish to change one style of posts for another, 105 for example a plain post to a sectional or extension-post. Moreover when a post breaks or becomes worn out, it is desirable to renew it without sending the binder back to the factory. Moreover by making the post removable, the amount of stock which it is necessary for the factory to keep on hand to fill orders is greatly reduced, as the different lengths of post and sizes of binder-back can be kept 110 separately and set up as ordered when the orders are received. These and similar advantages are effected by the use of my attachment means as herein described.

It will be seen from the above description that my invention is subject to certain 115 changes in the details and it should be understood also that not all the features shown are essential to the principles of my invention, as will be clear from the reasonable construction of my claims.

Having thus described my invention, what I claim as new and desire to secure by Letters Patent is:

1. Means for attaching a binder-post to its support comprising a base having a circu- 130

lar opening with a side-outlet narrower than the opening to receive the post and means on the end of said post for engaging and interlocking with the base, said means passing through said side-outlet and adapted to rotate in said hole.

2. Means for attaching a binder-post to its support comprising a base having a circular opening with a side-outlet narrower than the opening to receive the post and means on the end of said post for engaging said opening provided with a circular surface of the same diameter as said opening, flats on opposite sides thereof the width across which is the same as that of said side-outlet, and surfaces extending over the edges of said opening on both sides of said base.

3. Means for attaching a binder-post to its support comprising a base-plate having a circular hole therein and a side-outlet from said hole to one edge of the plate, said side-outlet being of narrower width than the diameter of said hole, a post-section, and an attachment-piece on the end of said post-section adapted to pass into said hole through said side-outlet and interlocking with the edges of said hole.

4. In combination with a laminar base having a buttonhole-slot therein, a removable post for binder-backs comprising a tubular cylindrical member having means for removably engaging said button-hole slot on the edges thereof and also on the opposite sides of said base.

5. In combination with a laminar base having a buttonhole-slot therein, a removable post for binder-backs comprising a cylindrical post-section having laminar flanges on the ends thereof separated by a distance substantially equal to the thickness of said base and adapted to extend over the edges of said slot; the body of said post-section being adapted to enter and rotate in said slot.

6. A removable post for binder-backs comprising a tubular post-section having flats cut on the sides thereof forming upstanding tabs between them, and an attachment-piece having a central body fitting in the bore of said post and having a pair of projecting flanges extending outwardly between said tabs; the projecting ends of said tabs being engaged with said attachment-piece.

7. A removable post for binder-backs comprising a tubular post-section having flats cut on the sides thereof forming upstanding tabs between them, and an attachment-piece having a central body fitting in the bore of said post and having a pair of projecting flanges extending outwardly between said tabs; the projecting ends of said tabs being bent and clenched down over the center of said attachment-piece.

8. A removable post-section for binders

comprising a tubular post-section having a pair of oppositely disposed flats cut on one end thereof leaving a pair of oppositely disposed tabs between said flats; and an attachment-piece having a central body portion fitting the bore of said post and lying between said tabs and two pairs of flanges extending outwardly from said body-portion between said tabs; the projecting ends of said tabs being clenched down over said central body-portion.

9. A removable post-section for binders comprising a tubular post-section having a pair of oppositely disposed flats cut on one end thereof leaving a pair of oppositely disposed tabs between said flats; and an attachment-piece having a central body portion fitting the bore of said post and lying between said tabs and two pairs of flanges extending outwardly from said body-portion between said tabs, the projecting ends of said tabs being clenched down over said central body-portion; in combination with a laminar base having a circular hole therein which has the same diameter as said post-section and a side-outlet of the same width as the distance across said flats.

10. Means for the attachment of posts to binder-backs comprising a laminar base having a circular hole therein connected with one edge of the base by a side-outlet of narrower width, a tubular post-section of the same diameter as said hole, projecting flanges extending outward from the post-section on opposite faces of said base, and filling-pads secured to said base on opposite sides thereof and having recesses which receive said flanges.

11. Means for the attachment of posts to binder-backs comprising a laminar base having a circular hole therein connected with one edge of the base by a side-outlet of narrower width, a tubular post-section of the same diameter as said hole, projecting flanges extending outward from the post-section on opposite faces of said base, and filling-pads secured to said base on opposite sides thereof and having recesses which receive said flanges, and a flexible covering sheet secured over said pads and recesses.

12. Means for the attachment of posts to binder-backs comprising a laminar base having a circular hole therein connected with one edge of the base by a side-outlet of narrower width, a tubular post-section of the same diameter as said hole, projecting non-circular flanges extending outwardly upon said post on opposite faces of said base, said flanges being separated by intervals of the same thickness as said base and the same width apart as the sides of said side-outlet whereby said post end is adapted to pass into said hole through said side-outlet and when rotated is non-removable through said side-outlet, a filling pad mounted on one side of said base

and having a recess therein which receives said flanges, and a projecting tab or like element on said filling-pad projecting into said recess and engaging said flanges to prevent the post from rotating.

13. A removable post-section for binders comprising a tubular post-section having a pair of oppositely disposed flats cut on the end thereof leaving a pair of oppositely disposed tabs between said flats; and an attachment-piece having a central body portion fitting the bore of said post and lying between said tabs and two pairs of flanges extending outwardly from said body-portion between said tabs, the projecting ends of said tabs being clenched down over said central body-portion; in combination with a laminar base having a circular hole therein which has

the same diameter as said post-section and a side-outlet of the same width as the distance across said flats, a pair of filling-tabs disposed on opposite sides of said base and having recesses therein which receive the flanges of said attachment-piece, and a projecting tab on one of said filling-pieces extending into the recess therein and between projecting elements on said flanges whereby it engages the attachment-piece and prevents it from rotating.

In witness whereof, I have hereunto set my hand this twenty-first day of May, 1908.
